United States Patent Office

Des. 224,081
Patented July 4, 1972

224,081

DRAPEY ROD

David M. Hadlow, Kensington, Conn., assignor to The
Stanley Works, New Britain, Conn.

Filed Jan. 22, 1969, Ser. No. 15,456

Term of patent 14 years

Int. Cl. D8—09

U.S. Cl. D8—208

FIG. 3
4
4

FIG. 4

FIG. 1 is a front elevational view of a drapery rod showing my new design;

FIG. 2 is a cross-sectional view along the lines 2—2 of FIG. 1;

FIG. 3 is a front elevational view of another embodiment of FIG. 1 wherein the rod is round in cross-section;

FIG. 4 is a cross-sectional view along the lines 4—4 of FIG. 3;

I claim:

The ornamental design of a drapery rod, as shown and described.
